UNITED STATES PATENT OFFICE

PAUL ERKENS, OF DUREN, GERMANY

LONG-SIEVE MACHINE FOR THE MANUFACTURE OF MULTIPLE-WEB PAPERS AND CARDBOARD

Application filed September 21, 1927, Serial No. 221,092, and in Germany November 21, 1924.

This invention has reference to long-sieve machines or so-called Fourdrinier-machines and in particular to machines of this kind, as employed in the manufacture of card-board or paste board or multiple-web papers and it is intended to facilitate the manipulation and increase the output of such machines and to generally improve the operation thereof. Paper machines of this general description have become known from the previous art in which the several webs of paper were combined at the couching points or shortly before reaching these points. Machines of this general operation were constructed on the principle of the so-called duplex and triplex machines. In view however of the fact that the shaking of the long-sieve does not take place at the couching points, it is obvious that the felting of the several webs of paper at their points of combination could not be satisfactorily and thoroughly carried out.

Now, this invention relates to a long-sieve paper machine for the manufacture of multiple-web papers and card boards in which a plurality of serially arranged long-sieve sections or units are employed adapted to operate independently of each other and particularly distinguished by the fact that these long-sieve units are disposed above the shaking portion of the long-sieve proper. In connection therewith it has been found to be advantageous to so arrange the several long-sieve units as to cause them to be shaken at the same ratio and parallel with relation to the long-sieve proper, and in further pursuance of my invention the compensating shaking of the long-sieve is effected only at the rear of the last unit.

The invention will be more fully described by way of exemplification of its general principles by reference to the accompanying drawing illustrating diagrammatically and in front elevation in Figure 1 the general arrangement of the principal constituent parts of the machine. Figure 2 is a plan view of Fig. 1.

Above the usual long-sieve 1 several machine-sieve units are disposed. In the exemplification shown three such units are employed and designated respectively 2, 3, 4.

The units are substantially duplicates of each other and comprise each the two rolls 5 and 6 and an endless long-sieve 7 and combined with the necessary suction boxes 8 and other appurtenances, a delivery table and so on which latter members have not been shown in the drawing. Below the point at the long-sieve 1 which is in contact with the roller 5 of the upper machine-unit and which constitutes the couching point a suction member 9 is arranged, in order to obtain an unobjectionable couching of the web. In front of the breast roll 10 of the long-sieve 1 a card-board forming roller with delivery table 11 is arranged. The guiding bars of the lower long-sieve 1 are divided behind the last unit 4 and the two rolls 12 constitute the pressing rolls of the sieve at the dividing point. The shaking is so arranged that the supporting bars of the frame section underneath the units 2, 3 and 4 and the section of the long-sieve 1 carried thereby are shaken in the parallel direction and at the same ratio as the machine units 2, 3 and 4 above the long-sieve. The section of the bars behind the two rollers 12 effects a compensating shaking operation in the well known manner. The units 2, 3 and 4 are arranged only above that part of the long-sieve 1 where the shaking takes place in the parallel direction and by this means a uniform couching across the entire width of the web of paper is accomplished.

The machine in accordance with this general description is particularly intended to serve for the manufacture of multiple-web paper or card-board by causing the several webs to be couched in superimposed relation upon each other. If it is intended for instance to manufacture bag paper, the machine unit 2 may be employed for instance, so as to couch a nice white web onto the long-sieve 1, while by means of the unit 3 an inferior intermediate layer is couched upon this web and an additional, for instance blue and high-grade web of paper is couched off from the last machine unit 4, so as to obtain a kind of paper or a card-board-like paper with differently colored outsides and with an intermediate layer or a filling of inferior, low-grade material. It is obvious that I may

also employ two machine units, while the first machine unit may for instance be replaced by the forming carriage with delivery table 11. It is also possible in accordance with this invention to manufacture thick, strong-walled card-boards by couching one card-board upon the other in accordance with the number of machine units. The thickness of the card-boards may be varied as desired and without any danger of the web of card-board dropping off or becoming detached from the long-sieve 1 which serves at the same time as a supporting conveying apron or band and this feature constitutes one of the important advantages as compared with the machines heretofore constructed in which the web of card-board or paper was couched onto the bottom side of the long-sieve.

As a further important advantage of the subject matter of this invention it may be pointed out that by this means it becomes possible to manufacture multiple-web papers and card-boards with interlacingly felted constituent webs and exhibiting very great tearing strength in the longitudinal as well as in the transverse direction and at a great economy of space.

The invention has been described and illustrated in its broad aspects and general features only, and it should be understood that it is not dependent upon the size and general arrangement of the several parts, except as otherwise stated in the appended claims.

I claim:—

1. In the art of making multiple-web paper, card board and the like, a shakily disposed, straight, web-supporting long-sieve, and a plurality of loop-shaped, shakily disposed, web-supporting sieves, serially and spacedly arranged in the direction of the long sieve and engaging said long sieve at one point of each of said loops, a guiding and pressing roller within the loops at the point of engagement with the long sieve and engaging the two runs of the loop, and a smaller supporting roller at the other end of each loop, spaced from the long-sieve, and couching means at the reverse side of the long-sieve at each point of engagement with the loops.

2. In the art of making multiple-web papers, card board and the like, a longitudinally travelling, shakily disposed, straight, web-supporting long-sieve, and a plurality of loop-shaped, longitudinally travelling, web-supporting sieves, serially and spacedly arranged in the direction of the long-sieve and co-directionally shakable with relation to the long sieve, and engaging the upper surface of the long-sieve at one point of each of said loops, a guiding and pressing roller within each of the loops at the points of engagement with the long-sieve

and engaging with the two runs of the loop, and a smaller supporting and guiding roller, engaging the inside of the other end of each loop and spaced from the long-sieve, and couching means at the reverse side of the long-sieve, at each point of engagement of the loops and opposite the respective comparatively larger roller.

PAUL ERKENS.
